No. 646,447.

Patented Apr. 3, 1900.

C. E. MORGAN.

AIR BRAKE.

(Application filed Sept. 22, 1897.)

(No Model.)

UNITED STATES PATENT OFFICE.

CHARLES EASTMAN MORGAN, OF PORTLAND, OREGON, ASSIGNOR, BY DIRECT AND MESNE ASSIGNMENTS, OF TWO-THIRDS TO DE WITT C. SOUTHWORTH AND ALBERT W. LAMBERT, OF SAME PLACE.

AIR-BRAKE.

SPECIFICATION forming part of Letters Patent No. 646,447, dated April 3, 1900.

Application filed September 22, 1897. Serial No. 652,587. (No model.)

To all whom it may concern:

Be it known that I, CHARLES EASTMAN MORGAN, a citizen of the United States, residing at Portland, in the county of Multnomah and State of Oregon, have invented certain new and useful Improvements in Air-Brakes; and I do hereby declare the following to be a full, clear, and exact description of the invention, such as will enable others skilled in the art to 10 which it appertains to make and use the same.

This invention relates to an improved air-brake mechanism more especially adapted for use on street-cars, and in its general construction embodies a novel pumping means having regulating devices operated by the motorman adapted to be set in operation from one of the truck-axles to charge up a reservoir carried on the car-body, from which at the will of the motorman air is fed into the brake-cylinder.

In its subordinate features this invention comprehends the peculiar combination and novel arrangement of parts, such as will be first described in detail and then be specifically pointed out in the appended claims, reference being had to the accompanying drawings, in which—

Figure 1 is a plan view of a car-truck frame having my improved air-brake mechanism applied, parts being in section. Fig. 2 is a top plan view, partly in section, of the air-holding reservoir and the top of the valve-chamber. Fig. 3 is a plan view of the slide-valve. Fig. 4 is a longitudinal section of the valve devices for regulating the connection of the pump and the brake-piston with the reservoir. Fig. 5 is a plan view of the motorman's shifting lever devices. Fig. 6 is a detail view illustrating the connection between the valve-stem and the motorman's shifting device.

Referring to the accompanying drawings, 1 indicates the car-truck of the ordinary construction, and 3 indicates a cross bar or beam to which the swinging brake-lever and the pump-cylinder are secured.

The pump-cylinder 4, connected to the beam 3 in any suitable manner, has its compression end connected by means of the pipe 6 with the air-holder 5, suitably mounted on the car and preferably centrally thereof, as it in prac-

tice is intended to supply air to the brake devices for the truck at each end of the car.

One end of the cylinder 4 is open to allow for the free play of the piston-rod, which is 55 pivotally joined to a cup-shaped piston in the usual manner.

The outer end of the rod 4^a is provided with a band 7, adapted to encircle an eccentric 8, loosely mounted on the car-axle 8^a and held 60 to abut a stationary collar 9 and a sliding clutch-collar 10 on such axle 8^a. The collar 10, which is held to rotate with the axle, is adapted to be moved into a tight frictional engagement with the eccentric 8, to make it 65 turn with it, by means of the lever 11, fulcrumed at one end on the truck-frame and having its other end secured to the rod 12 of a piston 4, operating in a subcylinder 13, formed integral with the pump-cylinder 4, into which 70 air is let, back of the piston 4, from the holder 5 through the feed-pipe 15.

So far as described the operation is as follows: When it is desired to charge the holder 5, communication is opened up between such 75 holder and the cylinder 13 by suitable valve-shifting mechanism under the control of the motorman, (which will hereinafter be fully explained.) The air-pressure forces the piston 14 inward and in consequence moves the 80 lever 11 to an apply position, which locks the clutch member 10 and the eccentric by frictional contact, causing them to rotate together, thereby setting the pump storing up 85 air to the holder 5. As soon as the air in the cylinder is exhausted the piston 14 and the lever 11 are returned to their normal position by the spring 27, the end of which is connected to the beam 3, as shown. The swinging 90 brake-lever 18 is secured to the beam 3 and has attached thereto at points opposite its fulcrum the brake-beam rods 20, which extend in opposite directions and connect with the brake-beams 19, as shown. The lever 18 is held to its released or normal position by the rod and spring devices 26 and is moved to its forward or braking position by the air-operated piston and rod 16^a, operating in the cylinder 16, which is charged when it is desired to apply the brakes from the main 100 reservoir or holder 5 by the pipe 17, which opens into the cylinder 16 at the front of the

piston and connects with the valve-chamber of the said holder, as clearly shown in Figs. 3, 4, and 5. By arranging the brake-apply-
5 ing devices as shown and described it is ob-
vious that so soon as a charge of air is opened
10 into the cylinder the lever 18 will be swung
in the direction indicated by the arrow and
the brakes applied, the force of such applica-
15 tion being at the will of the motorman, as will
10 presently appear.

In the practical application of my invention
15 any suitable shifting valve mechanism
under control of the motorman may be em-
ployed which will serve to feed and exhaust
the brake-cylinder, and as it so does cut out
20 the pump-cylinder, and for cutting in the
pump-cylinder as the brake-cylinder is cut
out.

The holder is provided in its valve-seat with
25 four feed-ports a' , a^2 , a^3 , and a^4 , one of which,
 a^4 , is located at the extreme right end. On
this valve-seat is arranged a reciprocating
slide-valve 25, provided with seven ports b' ,
30 b^2 , and b^3 , b^4 , b^5 , b^6 , and b^7 . The ports b' , b^3 ,
35 and b^5 are adapted to register with the feed-
ports a' , a^2 , and a^3 to supply compressed air
to the brake-cylinders and to the clutch-cyl-
40 inder in applying the brakes, and the port b^7
is adapted to register with the feed-port a^4 to
45 supply air to the clutch-cylinder for charging
the holder when not applying the brake. The
50 cap or top of the valve-chamber has three ex-
haust-ports c' , c^2 , and c^3 opening to the at-
mosphere. The pipe 17 at the left-hand end
55 of the holder is provided with leads 17^a and
17^b for the admission and exhaust of air, re-
spectively, and the right-hand pipe 17 is pro-
vided with reversely-arranged leads 17^c and
17^d. The pipe 15 has leads 15^a and 15^b for the
60 admission of air designed to be used, respec-
tively, when the brakes are being applied and
when charging the holder simply, and it is also
provided with an exhaust-lead 15^c, which is lo-
cated at a point between the leads 15^a and 15^b.
65 When the port b^7 of the slide-valve registers
with the feed for simply charging the cylin-
der, all the other ports of the holder are closed
and air passes through the said ports a^4 and
70 b^7 and enters the pipe 15 through the lead 15^b
and operates the clutch. Should the holder
be entirely empty, it is then charged by tem-
porarily locking the clutch-lever in its engag-
ing position by any suitable means, and after
75 the holder is charged the clutch-lever is re-
leased and can then be operated by com-
pressed air. The slide-valve is in the said
position when the motorman's lever is at the
80 notch 49. The pipe 17 at the right-hand end
of the holder in Fig. 1 communicates with
85 the brake-cylinder 16, as shown, and the pipe
17 at the left-hand end of the holder commu-
nicates with the brake-cylinder at the oppo-
site end of the car. By shifting the lever 23
90 to the position shown at 50 in Fig. 5 of the
drawings the valve is moved to the left and
the ports a^4 and b^7 are closed, and the port b^4
95 establishes communication between the ex-

haust-lead 15^c of the pipe 15 and the exhaust-
port c^2 of the top of the holder, thereby per-
mitting the air to exhaust from the pipe 15
10 and disengage the clutch. When the valve
is in this position, the ports b^2 and b^6 are also
in register with the ports c' and c^3 to permit
air to exhaust from the pipes 17 through the
leads 17^b and 17^d, and the valve is brought to
15 this position after an application of the brakes.
A movement of the valve to the notch 52 grad-
ually closes the exhaust-ports c' and c^3 and
partly opens the ports a' , a^2 , and a^3 by rea-
son of the ports b' , b^3 , and b^5 in the slide-valve
20 communicating therewith. By moving the
lever 23 still farther to the left to notches 53
54 the inlet-ports a' , a^2 , and a^3 will be grad-
ually opened to the fullest extent. When
the ports a' , a^2 , and a^3 are opened, air is ad-
25 mitted to the pipes 17 and 15 through the
leads 17^a, 17^c, and 15^a to apply the brakes and
operate the clutch to keep up the pressure in
the holder. After the brakes have been set
30 as tight as desired to hold them the lever 23
is moved to the right to the notch 51, which
adjustment moves the valve 25 to close off
the ports a' , a^2 , and a^3 and again partly
opens the exhaust-ports c^2 , which adjustment
35 of the valve and the several ports noted re-
leases the clutch, but does not permit the air
held within the pipe 17 to escape, as the said
movement of the valve 23 to the right at this
40 time also cuts off the leads 17^b and 17^d to the
said pipes 17, and thereby keeps the brakes
45 applied, which is advantageous, particularly
in descending a grade. Another movement
50 of the lever 23 to the right to the notch 50 will
carry the valve 25 back and bring its ports
55 b^2 , b^4 , and b^6 again into register with ports c' ,
 c^2 , and c^3 , (see Fig. 4,) which permits the air
60 to again exhaust from the pipes 17 and 15, as
before explained.

The shank or shaft 23^a of the motorman's
65 lever is provided with an arm 23^b, which is
connected with the valve-stem 25^a, and a pres-
sure-gage 24 is mounted upon the table to
70 keep the motorman posted as to the pressure
in the air-holder.

While the arrangement of the several parts
75 as illustrated in the drawings discloses the
general idea of my invention, it is manifest
the details of construction may be modified,
and changes, such as arranging the feed-ports
80 of the holder and the corresponding ports of
the slide-valve longitudinally of the holder to
effect a more gradual opening of the same,
85 may be made without departing from the
spirit of my invention.

I claim—

1. An air-brake, comprising a pump pro-
90 vided with a piston and piston-rod, an eccen-
tric loosely mounted on the car-axle, a collar
surrounding said eccentric and connected
95 with the piston-rod, an air-reservoir connect-
ed with the said pump and provided with open-
ings, a slide-valve mounted upon said air-
reservoir and having openings adapted to
100 register with the openings of the reservoir,

means for controlling the movements of the slide-valve, a cap for the slide-valve connected at each end with a brake-cylinder, a piston and piston-rod working in such cylinder, a 5 brake-lever attached to such piston-rod, brakes connected to said lever, an air-cylinder 14 in communication with the valve-cap, a lever 11 connected with the piston of the cylinder 14, and a collar mounted on the car- 10 axle and provided with a roughened face and adapted to be brought into engagement with the eccentric, substantially as described.

2. An air-brake, comprising a pump, a reservoir connected therewith and provided with 15 ports, brake-cylinders, pipes 17, connected with the latter, a clutch-cylinder, having a feed-pipe 15, a slide-valve having ports to register with those of the reservoir, and a valve-cap having exhaust-ports and provided 20 with feed and exhaust leads communicating

with the pipes 17 and arranged in pairs, said cap having a pair of feed-leads and an intermediate exhaust-lead communicating with the pipe 15, substantially as described.

3. In an air-brake, the combination of a 25 reservoir having ports a' , a^2 , a^3 and a^4 , a cap provided with central exhaust-ports c' , c^2 and c^3 , and having at one side feed and exhaust leads arranged in pairs, said cap being provided at the opposite side with feed-leads 15^a , 30 and 15^b , and an intermediate exhaust-lead 15^c , and the slide-valve provided with ports b' , b^2 , b^3 , b^4 , b^5 , b^6 and b^7 , substantially as described.

In testimony whereof I have signed this specification in the presence of two subscr- 35 ing witnesses.

CHARLES EASTMAN MORGAN.
